(57) **CLAIM**

The ornamental design for a lens with reticle, as shown and described.

DESCRIPTION

FIG. 1 is a front elevation view of a lens with reticle in accordance with my new design;

FIG. 2 is a reference view thereof showing the areas indicating from where enlarged details are taken;

FIG. 3 is an enlarged detail view of area 3 circumscribed within FIG. 2;

FIG. 4 is an enlarged detail view of area 4 circumscribed within FIG. 3;

FIG. 5 is an enlarged detail view of area 5 circumscribed within FIG. 3;

FIG. 6 is an enlarged detail view of area 6 circumscribed within FIG. 2 of a second embodiment of the lens with reticle;

FIG. 7 is an enlarged detail view of area 7 circumscribed within FIG. 6;

FIG. 8 is an enlarged detail view of area 8 circumscribed within FIG. 6;

FIG. 9 is an enlarged detail view of area 9 circumscribed within FIG. 2 of a third embodiment of the lens with reticle;

FIG. 10 is an enlarged detail view of area 10 circumscribed within FIG. 9; and,

FIG. 11 is an enlarged detail view of area 11 circumscribed within FIG. 9.

The dot-dash-dot broken lines are enlargement frames and lead lines that form no part of the claim. The broken line surrounding each of FIGS. 1 and 2 depicts the boundary of the claim and forms no part thereof. The evenly spaced broken lines in FIGS. 1 and 2 depict text forms no part of the claimed design. The evenly spaced broken lines in FIGS. 5-11 depict portions of the lens with reticle that form no part of the claimed design.
